ALFRED BURKE, OF FLUSHING, NEW YORK.

DISPLAY DEVICE.

1,213,455.

Specification of Letters Patent. Patented Jan. 23, 1917.

Application filed July 6, 1914. Serial No. 849,183.

To all whom it may concern:

Be it known that I, ALFRED BURKE, a citizen of the United States, residing at Flushing, in the county of Queens and State of New York, have invented certain new and useful Improvements in Display Devices, of which the following is a specification.

My invention relates to an improved device for displaying articles of merchandise, and it is designed especially for holding and displaying hair pins.

Celluloid, bone, shell or similar hair pins are usually mounted for sale on display cards, or are packed in boxes containing several pins and having one of them displayed on the front thereof. The devices heretofore used in vending hair pins have not been designed to securely hold the displayed pins in place, and it has been found that many of the pins are lost or damaged in the handling which they receive during inspection and sale.

The principal object of my invention is to provide a display device having novel means for securely holding a hair pin in place thereon and which is constructed so that the displayed pin cannot be accidentally dislodged in handling the device.

I attain the object specified as well as others not herein enumerated by means of the construction and arrangement of parts hereinafter described and shown in the accompanying drawings, in which:

Figure 1 is a front view of one form of display device embodying my invention, Fig. 2 is a view of a modification of the device made in the form of a box blank, Fig. 3 is a view in perspective of the folded box blank, and, Fig. 4 is a transverse vertical section thereof, when closed.

My improved device consists of a body portion made of card board or other suitable material having means formed thereon for engaging the head and the points of a hair pin. It is constructed so as to securely hold and lock the hair pin in place when it is mounted thereon.

Referring to the drawings, 1 represents the body portion of the device consisting preferably of a piece of card board cut in any convenient or desired shape and size. In said body are formed two slits, indicated by reference characters 2 and 3, leaving an integral vertical bar or strip 4 of the ma-

terial separating them, which strip serves as a retaining member for holding and securing the curved head of the pin 5. The ends of the slits 2 and 3 are preferably curved outwardly, as shown, to strengthen the connection between the strip 4 and the body.

Two horizontal bars or strips 6, formed integral with the body portion, are located in position to engage the legs of the pin 5. These strips are made by forming cuts 7 in the material directly above and below the place where it is desired to locate the strips.

Extending laterally of the strip 4 are the slits 8, 8, which terminate at points located a greater distance apart than the maximum width of the pin so as to form a divided pin-receiving opening of a total length sufficient to permit the pin 5 to be freely passed therethrough. In mounting the pin it is inserted from the back of the body 1, through the opening formed by said slits, into position shown in Fig. 1 with the legs of the pin caught in the strips 6 and the head thereof engaged by the strip 4. After the pin has been inserted through the slits 8, the portions of the card board body surrounding the opening will spring back to their normal position so as to securely hold the head of the pin in place between said body and the strip 4.

In Figs. 2 and 4 of the drawings I have shown a modified construction of the device in which the body portion 1 is made in the form of a box blank. With this form of my invention I am able to securely hold and display one of the pins on the front thereof, in the manner heretofore described, and then to fold the parts of the blank so as to form a package or box in which a plurality of the pins may be conveniently packed. In the modified form, the body 1 is extended along its sides and also at its top and bottom so as to provide sufficient stock to permit of its being folded into box like shape after the displayed pin has been secured to the front thereof. To this end the side extensions are creased along vertical lines 9, 10, 11 and 12 and are then folded inwardly to form the walls and central partition of the boxlike package shown in Figs. 3 and 4. The portion *a* of the blank lying between the pair of creases 9 forms the front wall of the box; the portions *b* between the creases 9 and 10 the side walls; the portions

c between the creases 10 and 11 each of which is approximately one half the width of the front portion *a*, together form the rear wall; the portions *d* between the creases 5 11 and 12 form the central partition; and the end portions *e*, form flanges which are adapted to abut against the front wall of the box when in folded position and serve to hold the partition *d* in place. The top 10 and bottom extension of the body portion 1, are each cut to form two side flaps *f* which are adapted to be folded inwardly in overlapped relation so as to close the open ends of the box, and a cover flap *g* having a bifurcated extension which is adapted to be folded down upon the flaps *f* to close the box 15 and to hold the folded parts thereof together. The extended portion of the cover *g* fits into the space between the rear edges 20 of the flaps *f* and the rear wall *e* of the box so that the divided parts thereof will exert a clamping action on the opposite sides of the partition *d* and thereby hold the folded box together without necessity of gluing or 25 pasting any of its parts. When the pins are packed in the box they are supported by and ride upon the partition *d* as best seen in Fig. 4.

30 In the foregoing specification I have described what I believe to be the best mode of applying my invention, but it will be understood that the construction and arrangement of the various parts may be modified from that illustrated in the accompanying drawings without departing from the scope 35 of my invention.

What I claim and desire to secure by Letters Patent is:

1. A display device for hair pins comprising a blank provided with a pair of slits forming a holder between them for the head of a pin, slits extending laterally of said pair of slits and terminating at points located a greater distance apart than the maximum width of the pin, and holders for 40 the legs of the pin, said lateral slits forming a divided opening through which the pin is passed into engagement with the holders in mounting it on the blank. 45

2. A display device for hair pins comprising a card provided at its upper portion with a pair of longitudinal slits having outturned ends and forming between them a vertical strip for engaging and holding the head of a hair pin, slits extending 50 laterally of the longitudinal slits and forming a divided pin-receiving opening of greater length than the width of the pin whereby the pin may be mounted on the card by being passed from the rear through 55 said opening, and pairs of transverse slits having outturned ends at the lower portion of the card and forming between them horizontal strips for engaging and holding the legs of the pin. 60

In testimony whereof, I have hereunto affixed my signature in the presence of two subscribing witnesses.

ALFRED BURKE.
